Patented Dec. 6, 1921

INVENTOR
Henry J. Karp
BY HIS ATTORNEY

James F. Williamson

UNITED STATES PATENT OFFICE.

HENRY J. KARP, OF FARIBAULT, MINNESOTA.

DESIGN FOR A CLOCK-STAND.

59,896.

Specification for Design.

Patented Dec. 6, 1921.

Application filed April 25, 1921. Serial No. 464,472. Term of patent 3½ years.

To all whom it may concern:

Be it known that I, HENRY J. KARP, a citizen of the United States, residing at Faribault, in the county of Rice and State of Minnesota, having invented a new, original, and ornamental Design for a Clock-Stand, of which the following is a specification, reference being had to the accompanying drawing, forming part thereof.

The single view is a front elevation illustrating my "clock stand."

I claim:—

The ornamental design for a clock stand, as shown.

HENRY J. KARP.

Witnesses:

FRIDOLIN SCHIMMEL,
HENRY SCHLATTER.
